UNITED STATES PATENT OFFICE.

JOHN I. THOMPSON, OF PITTSBURGH, PENNSYLVANIA, ASSIGNOR TO THE KOPPERS COMPANY, OF PITTSBURGH, PENNSYLVANIA, A CORPORATION OF PENNSYLVANIA.

ACID REGENERATOR.

1,402,194.

Specification of Letters Patent. Patented Jan. 3, 1922.

Application filed August 4, 1919. Serial No. 315,111.

To all whom it may concern:

Be it known that I, JOHN I. THOMPSON, a citizen of the United States, residing in Pittsburgh, in the county of Allegheny and 5 State of Pennsylvania, have invented a new and useful Improvement in Acid Regenerators, of which the following is a specification.

This invention relates generally to a 10 dumping receptacle apparatus, and has one especially valuable application as an acid regenerator of a benzol recovery plant. It will be understood, however, that the invention is capable of other valuable applications 15 than the specific use here mentioned and described in the ensuing specification.

A highly important object of the invention is the provision of a dumping receptacle apparatus having a fixed cover and a receptacle mounted beneath and movable toward and from said fixed cover. This novel construction permits the connection of relatively fixed supply and exhaust means with the fixed cover and consequently enables 25 dumping of the receptacle without the necessity of disturbing the supply and exhaust means leading toward and from the fixed cover of the receptacle. When utilized as an acid regenerator for benzol recovery plants, 30 a dumping receptacle apparatus having these characteristics permits ready, quick and easy removal of the refuse from the receptacle, without detaching the fluid conducting connections, thereby attaining a much less laborious dumping operation and also reducing the leakage of vapors about the plant.

Heretofore, in benzol recovery plants, relatively fixed acid regenerators have been employed for regenerating or recovering the 40 acid from the sludge discharged from the agitator. When the recovery of the acid has been effected in the regenerator, there remains a disagreeably odoriferous spongy refuse material in the bottom of the regenerator, which prior to this invention has been removed by the laborious expedient of digging it out from the bottom of the regenerator with a spade. This cleansing operation is invariably one of a very disagreeable nature, owing to the characteristics of the refuse material and the necessity of having an attendant get down into the regenerator to remove the refuse material. By the employment of the present invention, this disagreeable and laborious cleansing operation is en-

tirely obviated and the receptacle of the acid regenerator may be readily cleansed, by simply moving the receptacle to a dumping position and raking out the refuse material from the receptacle.

With the above and other objects in view, the invention consists in certain novel constructions, arrangements, and combinations of parts hereinafter described in a preferred form, as an illustrative example, and particularly set forth in the claims at the end of the specification.

In the drawings,

Figure 1 is a sectional elevation of a portion of a benzol recovery plant equipped with an acid regenerator, constructed in accordance with the present improvements;

Fig. 2 is a top plan view of a pair of acid regenerators, illustrating the supply and exhaust means respectively leading to and from said regenerators;

Fig. 3 is an enlarged top plan view of an acid regenerator;

Fig. 4 is a vertical sectional elevation of the same;

Fig. 5 is an end elevation looking from the right of Fig. 4;

Fig. 6 is an enlarged detailed view of the latch mechanism;

Fig. 7 is a fragmentary side elevation of 85 said latch mechanism looking from the left of Fig. 6;

Fig. 8 is a vertical sectional elevation of the drain valve, and,

Fig. 9 is a horizontal sectional elevation 90 of said valve taken in a plane indicated by the line 9—9 of Fig. 8.

In the illustrated embodiment of the invention, the dumping receptacle apparatus is especially adapted for use as an acid regenerator for recovering the acid in the sludge discharged from the agitator of a benzol recovery plant, and for convenience the present invention will be confined to this use of the invention. Features of construction of the dumping receptacle apparatus, are, however, readily susceptible to other valuable applications, and it is manifest that the scope of the invention is by no means confined to the specific application and specific 100 embodiment herein described.

Referring to the drawings, there is shown in Fig. 1 a portion of a benzol recovery plant having an agitator 11 of any preferred type. In said agitator, benzol is thoroughly 110

mixed with acid for the purpose of separating the unsaturated hydro-carbons, chiefly phenols and olefins. These impurities form with the acid a thick bluish sludge which 5 on account of its high specific gravity settles out in the bottom of the agitator and is discharged through a sludge trough 12 leading to the acid regenerator. If desired, said sludge trough 12 may be utilized as a supply main for a pair of regenerators, as 10 shown in Fig. 2, and for this purpose the sludge trough is equipped with a pair of spouts 13 respectively extending to each unit of the pair of regenerators.

15 Although it is the usual practice to employ a series of acid regenerators in a benzol recovery plant, all of the regenerators are alike in construction, and for this reason the description will be confined to a single regenerator.

In its essentials, the regenerator 15 embodies a fixed lid or cover 16 and a receptacle or pot 17 movable toward and from said fixed cover. As shown in Figs. 3 to 5 inclusive, the cover 16 may be a substantially elliptical plate member 18, on which are mounted two pairs of spaced longitudinally-extending angle bars 19, 20, the respective pairs being connected and braced by a transversely-extending angle bar 21. Each pair of angle bars is rigidly secured to supporting plates 22, 23, and the latter in turn are secured between pairs of channel irons 24, 25 extending longitudinally of and secured 30 beneath transverse beams 26 of the framework structure of the recovery plant. Mounted on the plate member 18 of the fixed cover is a sludge nozzle 27 of any approved construction and communicating with a registering opening in said plate member 18. The sludge nozzle is adapted to be connected with a sludge spout 13 of the sludge trough 12, thereby providing a means for supplying sludge to the interior of the receptacle 45 17 of the acid regenerator. Also mounted on the plate member 18 of the fixed cover is a vapor nozzle 28, preferably formed with a side wall tapering toward the top and adapted to be connected with a vapor ascension pipe 29, see Figs. 1 and 2, which leads to a vapor collecting main 30 extending along the entire battery of regenerators in the recovery plant. The lower end of the vapor nozzle communicates with a registering opening in the plate member 18, and the vapors from the receptacle or pot 17 passes 55 through said opening and nozzle 28 into the ascension pipe 29 and finally through the vapor collecting main 30 to a suitable condenser, where the vapor may be condensed and any remaining benzol separated from it. If desired, the plate member 18 of the fixed cover may also be provided with an inspection hole 31 adapted to be closed by 60 a removable cover 32. Preferably the fixed

cover is provided with a depending peripheral flange 33 for a purpose which will hereinafter appear. The receptacle or pot 17 comprises a suitable metallic outer shell 34, preferably of a hopper scuttle-shaped configuration, so as to provide a mouth that is substantially unrestricted with respect to the interior of the receptacle or vessel, and having a long gradually-inclined front wall 35, a short relatively-steep rear wall 36 and 70 a dished bottom 37 inclined downwardly toward the front wall 35. The entire interior of the shell is lined with fire brick, or other refractory material, as indicated at 38. The shell 34 is open at the top and is preferably 75 formed with an outwardly-flaring peripheral flange 39 which receives the depending flange 33 of the fixed cover, when the receptacle, or pot is in operative relation with respect to such fixed cover. 80

The receptacle or pot is fulcrumed on an axis beneath the fixed cover, whereby said receptacle may be tilted toward and from the fixed cover, and for this purpose there is mounted on the rear wall 36 a pair of 90 transversely spaced brackets 40, provided with aligned holes through which is passed and rigidly secured to said bearing brackets 40 a hollow shaft or pipe 41. The pipe 41 is journaled at its opposite ends in bearings 95 42 respectively secured between a pair of channel bars 43 of the fixed building-structure. With this construction, the entire receptacle and pipe 41 may be tilted about a horizontal axis in the fixed bearings 42. 100

A means is provided for retaining the receptacle or pot in operative relation with respect to the fixed cover and for this purpose a manually-operable latch mechanism is utilized, as illustrated in detail in Figs. 105 6 and 7. As shown the opposite sides of the shell 34 of the receptacle are provided with projecting lugs 44 for co-operation with the respective hooks 45 at the lower ends of a pair of transversely spaced latch 110 levers 46 pivoted at the point 47 between a pair of transverse channel bars 26 of the fixed frame structure. The upper ends of said latch levers 46 are respectively provided with pivoted blocks 48 in which are 115 threaded, the opposite screw threaded ends 49, 50 of an operating shaft 51. This operating shaft 51 is journaled in a suitable bearing 52 mounted on the channel bars 26 and is provided with hand wheel 53. The 120 screw threaded ends 49, 50 of said shaft 51 are of opposite pitch, and by turning the hand wheel 53 in one direction the pair of latch levers 46 may be moved toward each other to shift the hooks 45 beneath the lugs 125 44 of the receptacle and to retain the latter in operative relation with respect to the fixed cover. Movement of the hand wheel 53 in the opposite direction will shift the hooks 45 from beneath the lugs 44, permit- 130

ting the receptacle to be lowered into dumping position.

The hoisting and lowering movements of the receptacle 17 are preferably controlled by a hoist. As shown in Figs. 4 and 7 the opposite side walls of the receptacle are formed with projecting studs 54, which respectively receive eyes 55 carried by the lower ends of a pair of vertical hoist bars 56. The hoist bars 56 extend vertically upwardly to the roof of the regenerator chamber as shown in Fig. 1, and may be elevated and lowered by any suitable means to effect elevation and lowering movement of the receptacle.

Mounted in the bottom 37 of the receptacle is a valve-controlled drain 57. This drain is preferably constructed of a suitable casing 58 projected through an opening in the bottom of the receptacle and secured by bolts 59 to a flange 60 formed on the bottom wall 37 of the receptacle. The casing 58 is provided with an outlet nozzle 61 disposed at an angle with respect to the main portion 25 of the casing and adapted for connection with a suitable drain pipe 62; as shown in Fig. 1. Mounted on a valve stem 63 and located at the upper end of the casing 58 is a valve head 64 provided with axially disposed ribs 65. The valve stem 63 extends through a gland 66 located at the bottom of the casing and within a yoke 67 secured to the bottom of said casing. The lower end of said stem 63 is provided with screw threads, as at 68, for engagement with interior threads of an operating nut 69 rotatably mounted in the lower end of the yoke 67. A head 70 is formed on the upper end of the operating nut and screwed on the lower end thereof is an operating handle 71, the head 70 and handle 71 mutually preventing axial movement of the operating nut 69. Formed in the valve stem 63 is an axial groove 72 which receives the inner end of 45 a key 73 mounted in the side of the yoke 67 and projecting laterally inwardly therefrom. The key working in the groove 72 prevents rotation of the valve stem 63, while permitting it to move axially as desired. 50 With the above valve construction a rotation of the operating handle in one direction will cause the valve stem 63 and head 64 to travel upwardly out of the valve casing and into the interior of the receptacle 55 17, thereby forcing a passage through any sediment or solid matter in the bottom of the receptacle and permitting liquid to drain through the valve casing and outlet 61 to the drain pipe 62. On rotation of the operating handle 71 in the opposite direction the valve head 64 is retracted within the casing 58 to close the valve. As shown in Figs. 1 and 4, the valve-controlled drain is preferably located at approximately the lowermost point of the receptacle, in order

that all of the liquid which settles out in the bottom of the receptacle, will drain through the valve casing.

Heat for separating the acid and vapor from the solid matter, in the sludge discharged into the regenerator receptacle 17, is conveniently supplied by means of a steam nozzle 74. The nozzle 74 projects within the regenerator receptacle 17 and is conveniently secured by bolts 75 to a flange 76 projecting from the bottom wall 37 of the receptacle. Coupled with the nozzle 74 is a steam hose 77 which extends to the pipe 41. The pipe 41 may be utilized as a steam supply pipe through which steam flows from any suitable source of supply to the hose 77 and thence to the steam nozzle 74 which injects steam into the interior of the regenerator receptacle.

The general plan of operation of an acid regenerator, as above preferably constructed, in a benzol recovery plant is the following:

The thick bluish sludge from the agitator 11 is discharged through the sludge trough 12 and sludge spout 13 to the sludge supply 90 nozzle 27 of the fixed cover, and the sludge passes through such supply nozzle into the regenerator receptacle 17. When the receptacle is about two-thirds full, the sludge supply from the agitator may be shut off and the joint between the flaring flange 39 of the receptacle and the depending flange 33 of the fixed cover is luted with mud. Steam is then turned into the receptacle 17 through the steam nozzle 74 and the sludge is boiled 100 from four to ten hours. During the boiling of the sludge, the rising vapors pass through the vapor nozzle 28 and ascension pipe 29 to the vapor collecting main 30, which carries the vapor to the condenser. After the 105 sludge is thoroughly boiled to a crisp spongy mass the steam is shut off. The valve-controlled drain 57 is then opened and the regenerated acid drained off through the drain outlet 61 and drain pipe 62. Said drain 110 pipe 62 extends to an acid filter tank 78 through which the acid passes before it is finally discharged into the acid drain tank 79. When all the acid is drained from the receptacle 17, the hoist bars 56 are elevated 115 to take the weight of the receptacle from the latch mechanism and the latch mechanism is operated to release the latch in the manner hereinbefore described. The hoist is then operated to lower the receptacle 17 120 to a position such as indicated in dotted lines in Fig. 1. When in such lowered or dumping position the spongy ill-smelling refuse in the bottom of the receptacle 17 may, by reason of the wide open hopper-like mouth 125 of the receptacle, be simply raked into a refuse car 80, which travels on a track 81 located beneath the receptacle 17. As soon as the receptacle is thoroughly cleaned, it is again hoisted by means of the hoist bars 56, 130

4
into operative relation with respect to the fixed cover and the acid recovery operation repeated.

The above invention as hereinbefore set forth is embodied in a particular form or construction but may be variously embodied within the scope of the claims hereinafter made.

I claim:

10 1. In an acid regenerator, in combination: a fixed lid; and a hopper-mounted receptacle mounted beneath and movable toward and from said lid, into and out of position for being closed thereby; substantially as specified.

15 2. In an acid regenerator, in combination: a fixed lid; and a regenerative receptacle having a mouth substantially unrestricted with respect to the interior of the receptacle, 20 said receptacle being fulcrumed on an axis beneath said fixed lid, so as to be tiltable into and out of position for being closed thereby; substantially as specified.

25 3. In an acid regenerator, in combination: a fixed lid; fluid-conducting means connected with said fixed lid; and a regenerative receptacle having a mouth substantially unrestricted with respect to the interior of the receptacle, 30 said receptacle being fulcrumed on an axis beneath said fixed lid, so as to be tiltable into and out of position for being closed thereby; substantially as specified.

35 4. In an acid regenerator, in combination: a fixed lid; a regenerative receptacle having a mouth substantially unrestricted with respect to the interior of the receptacle, said receptacle being mounted beneath and movable toward and from the fixed lid into and 40 out of position for being closed thereby; and releasable means for retaining said receptacle in closed relation with respect to said fixed lid; substantially as specified.

45 5. In an acid regenerator, in combination: a fixed lid; a regenerative receptacle having a mouth substantially unrestricted with respect to the interior of the receptacle, said receptacle being fulcrumed on an axis beneath said fixed lid, so as to be tiltable into 50 and out of position for being closed thereby; and means for hoisting and lowering said receptacle on its axis; substantially as specified.

55 6. In an acid regenerator, in combination: a fixed lid; a regenerative receptacle having a mouth substantially unrestricted with respect to the interior of the receptacle, said receptacle being fulcrumed on an axis beneath said fixed lid, so as to be tiltable into

and out of position for being closed thereby; releasable means for retaining said receptacle in closed relation with respect to said fixed lid; and means for hoisting and lowering said receptacle on its axis; substantially as specified.

60 65

7. In an acid regenerator, in combination: a fixed lid; a sludge-supply spout and a vapor pipe connected with said fixed lid; a hopper-mouthed sludge boiler receptacle fulcrumed on an axis beneath and tiltable 70 toward and from said fixed lid; releasable means for retaining said receptacle in closed relation with respect to said fixed lid; and means for hoisting and lowering said receptacle on its axis; substantially as specified.

75 8. In an acid regenerator, in combination: a fixed lid; a sludge-supply spout and a vapor pipe connected with said fixed lid; a hopper-mouthed sludge boiler receptacle 80 fulcrumed on an axis beneath and tiltable toward and from said fixed lid; a valve-controlled drain mounted in the bottom of said receptacle; releasable means for retaining said receptacle in closed relation with respect to said fixed lid; and means for hoisting and lowering said receptacle on its axis; substantially as specified.

9. A dumping receptacle apparatus, comprising, in combination: a fixed lid, and a 90 hopper-mouthed dumping receptacle mounted beneath and movable independently of said lid into open position and into position for being closed by said fixed lid, substantially as specified.

95

10. In an acid regenerator, in combination: a fixed lid, a hopper-mouthed receptacle mounted beneath and movable toward and from said fixed lid; and means connected with said fixed lid for supplying to 100 the receptacle the material to be treated in said receptacle; substantially as specified.

11. A dumping receptacle apparatus, comprising, in combination: a fixed lid, and a 105 dumping receptacle having a mouth substantially unrestricted with respect to the interior of the receptacle, said receptacle being mounted beneath and movable independently of said lid into open position and 110 into position for being closed by said fixed lid, substantially as specified.

Signed in the presence of two subscribing witnesses.

Certificate of Correction.

It is hereby certified that in Letters Patent No. 1,402,194, granted January 3, 1922, upon the application of John L. Thompson, of Pittsburgh, Pennsylvania, for an improvement in "Acid Regenerators," errors appear in the printed specification requiring correction as follows: Page 4, line 11, claim 1, for the words "hopper-mounted receptacle" read *hopper-mouthed receptacle*; same page, line 16, claim 5, for the misspelled word "unrestircted" read *unrestricted*; and that the said Letters Patent should be read with these corrections therein that the same may conform to the record of the case in the Patent Office.

Signed and sealed this 27th day of June, A. D., 1922.

[SEAL.]

KARL FENNING,

Acting Commissioner of Patents.
